Atty:

UNITED STATES PATENT OFFICE

PAUL L. GODDARD, OF OAK PARK, ILLINOIS, ASSIGNOR TO CENTRAL WAXED PAPER COMPANY, OF CHICAGO, ILLINOIS, A CORPORATION OF ILLINOIS

ICE-CREAM-CONTAINER LINER

Application filed May 2, 1927. Serial No. 188,316.

The invention relates in general to ice cream containers, packages, and the like, and refers more particularly to an improved die-cut ice cream brick wrapper and carton liner.

Ice cream is packed for commercial distribution by forming a cardboard carton having a waxed paper lining and pouring semi-frozen ice cream into the container thus formed through an open end. This end is then folded shut and the filled carton placed into a refrigerator and frozen into solid form. It is desirable, from both a hygienic and an economic standpoint, to package the ice cream by machine. Contamination of the product from human handling is thus eliminated and the benefits of mass production secured. Various forms of carton liner are now on the market, all of which are more or less unsatisfactory because of the tendency of the liner to tear while being folded for insertion in the carton. The liner is first wrapped about a mandrel comprising a wood block of a shape and size equal to that of the finished brick. The liner wrapped mandrel is then inserted into the carton and the mandrel withdrawn leaving the liner frictionally engaging the inner sides of the carton. After the ice cream has been poured in and frozen the carton liner becomes a brick wrapper and is removed from the carton together with the brick when the latter is removed for consumption. The wrappers now used comprise substantially rectangular sheets of waxed paper of length sufficient to enfold the sides of the mandrel and having sufficient width between longitudinal edges to cover the sides of the mandrel and to extend therebeyond, to provide a surplus at each end which may be folded over to cover the ends of the mandrel. To facilitate the folding of these end portions over the brick ends, the liner is frequently provided with slots extending from the edge of the liner inwardly to adjacent the body of the mandrel and which are disposed in the liner opposite the corners of the mandrel. These slots also facilitate the folding of the open end of the liner after the ice cream has been poured into the container because the edge of the wrap-

per is thus divided into segments having lengths equal to the width of the brick sides and providing flaps which may easily be folded over the ends of the semi-fluid ice cream brick. The slots, however, provide a starting point for tears, and if the liner is not placed in exact position about the mandrel so that the slots are disposed opposite the corners thereof, or if the liner is improperly positioned within the carton, strains will be induced in the liner material and the liner may become so torn or otherwise damaged as to require rejection of the package.

The cut flaps also provide a source of faulty folding. Since the flaps have perpendicular sides, their outer corners will project beyond the plane of the adjacent side of the container and engage adjacent flaps, if the wrapping has not been applied with accuracy, or if the carton is slightly mis-shaped. Such a projecting portion may catch upon the carton or upon the wrapping machinery and become torn; or, if the wrapping is successfully accomplished, the final package may lack a desirable neatness of appearance.

The principal object of the invention is the provision of an improved die-cut ice cream brick wrapper and carton liner of such form as will reduce to a minimum the tearing of the wrapper material during its application to a brick.

Another important object of the invention is the provision of an improved liner or wrapper for ice cream cartons which is adapted to accommodate slight variations in the size and shape of the carton and also some variation in the positioning of the liner therein.

Another important object is the provision of an improved insert liner for ice cream cartons having tapering slots to provide convenient flaps for folding about the end of a mandrel or a poured ice cream brick to eliminate tearing of the liner material.

Still another important object of the invention is the provision of a liner for ice cream cartons having slots formed therein to facilitate the folding of the wrapper about the end of a mandrel or a poured ice cream brick, which slots are provided with rounded

apexes to prevent tearing of the wrapper at that point during folding operations and to allow the liner to successfully accommodate slight variations in the dimensions of the 5 lined ice cream carton.

Numerous other objects of the invention will be apparent as it is better understood from the following description, which, taken in connection with the accompanying drawings, discloses a preferred embodiment thereof.

Referring to the drawings:

Figure 1 is a perspective view of a mandrel enclosed in an improved liner embodying my invention;

Fig. 2 is a perspective view of an end of a mandrel and liner folded therearound and illustrating the improved folding flaps of the liner;

Fig. 3 is an enlarged plan view of the preferred form of the slotted portion of the liner; and

Fig. 4 is a plan view of the liner.

I have shown on the drawings a mandrel or a brick of ice cream 11 of standard size enclosed in an improved wrapper 12. The drawings illustrate equally well the finished ice cream brick as it is when withdrawn from the carton for consumption wrapped in the 30 carton liner. The wrapper or liner comprises a rectangular sheet of waxed paper or similar convenient wrapping material having opposite long edges 16 and 16' and short edges 17 and 17' and is adapted to enclose a 35 mandrel with the short edges 17 and 17' parallel to the long edges of the mandrel and having long edges 16 and 16' overlying the ends of the mandrel. The liner is provided with a plurality of die-cut slots 13 having 40 converging sides 14 and rounded apexes 15 positioned in that edge of the liner which is adapted for folding about the end of the brick. The slots are arranged in the liner at right angles to the edge and have apexes 45 disposed respectively at the points in the liner which are arranged to engage the edge corners of the mandrel. The liner provides a mid-section 18 comprising portions 21, 22, 23, 24 and 25 arranged adjacently along the 50 liner and adapted to embrace respectively the top, side, bottom, side and top of the mandrel being bent from each other along lines of bend 26, 27, 28 and 29 to provide such engagement, and edge sections 19 and 55 19' disposed on each side of the mid-section 18 and comprising portions 31, 32, 33, 34 and 35 adjacent edge 16 of the wrapper and portions 31', 32', 33', 34' and 35' adjacent edge 60 16'. These edge portions adjoin the corresponding mid portions 21, 22, 23, 24 and 25 and are adapted to be folded therefrom about the mandrel ends before the mandrel is thrust into the carton and along lines of bend comprising lines 36 and 36', which

divide the mid-portion 18 from the edge portions 19 and 19' respectively.

The mandrel is wrapped by bringing portion 21 of the mid section 18 into engagement with the top side of the mandrel. The 70 portions 22, 23 and 24 are then successively engaged with the side, the bottom and the other side of the mandrel, the wrapper being folded along the lines 26, 27 and 28 between adjacent portions. Portion 25 then is bent 75 from portion 24 along line 29 and folded over the portion 21 which is already disposed on the top of the mandrel. When the sides of the mandrel have been thus wrapped the section 19' extends beyond the end of the 80 mandrel and is folded down over the end of the mandrel as a final step in the wrapping. The mandrel with the wrapper is then inserted in the carton, the flaps of edge portion 19 extending out of the open end of the 85 carton when the mandrel is withdrawn.

It may be found desirable to provide slots in the liner in both edge sections 19 and 19'. However, as the main object of my invention is to provide a liner having end flaps easily 90 foldable over the poured ice cream brick, I have illustrated the slots in section 19 only, section 19' being shown folded about the end of the mandrel in the usual manner, that is to say, the adjacent engaged portions 31' and 35', which are continuations of portions 21 and 25 of the mid section 18 are first bent downwards along portions of line 36' and 95 folded upon the end of the mandrel. To permit this, portions 32' and 34' are simultaneously folded about the diagonal lines 42 and 44, lines 26' and 29' becoming adjacent to line 36'. The folded portions 32' and 34' are next bent from portions 22 and 24, of which they are lateral extensions, along portions of the line of bend 36' and along the lines 26' and 29', the portion 33' being twice 100 folded upon itself along lines of bend 43, lines 27' and 28' becoming adjacent to each other and to that portion of line 36' which 105 divides portions 23 and 33'. The twice folded portion 33' finally is bent from portion 23 on the line 36' and engages the end of the 110 mandrel over the portions 31', 32', 34' and 35' which have already been folded there-over.

Before folding the other end of the liner, the mandrel and liner are slid into the carton and the mandrel withdrawn and ice cream 110 poured into the carton. This fills the carton liner which becomes an ice cream brick wrapper. The upper edge of the wrapper is then folded about the semi-fluid brick and the package completed.

In order to simplify the folding operations it is customary to slit the end sections 19 and 19' along the continuation of lines 26, 27, 28 and 29 and thus to separate the adjacent portions 31, 32, 33, 34 and 35 to provide flaps which may be separately folded over the end 130

of the brick without affecting the adjacent flaps. This arrangement has several inherent disadvantages. The sharp apex of the slot provides an ideal starting point for a tear, and the wrappers heretofore provided are frequently so badly torn during the wrapping process that they have to be discarded. Furthermore, if the carton containing the brick is not perfectly rectangular or 5 has a side which is longer or shorter than the distance between the slots in the wrapper, the slot will not coincide with the corner of the carton or brick and the benefits which accrue from slitting the wrapper, viz., ease and neatness in folding do not appear. This situation 10 is encountered even when the carton is perfectly formed if the liner is not inserted in the carton having inner slot ends coinciding with the corners of the carton. Another important 15 defect is noticeable if the final wrapper folds are improperly made. If a flap is not folded exactly along the line 36, the corners of the flap project laterally and engage adjacent flaps making the folding difficult.

20 To overcome these disadvantages I have provided a liner having specially shaped slots 13, the sides 14 of which are spaced apart and the inner ends 15 of which are formed as rounded heads. In the preferred form 25 of slot the sides 14 converge to an apex. The rounded apex provides a maximum resistance to tearing, and also allows a slight adjustment of the liner within the carton to accommodate slight variations in the size and shape 30 of the carton. The spacing of the sides of the slot provides end flaps having sides which will not engage or interfere with the adjacent flaps or project beyond the plane of the sides 35 of the carton if the flap is misplaced in folding.

40 It is thought that the invention and many of its attendant advantages will be understood from the foregoing description, and it will be apparent that many changes may be made in the form, construction and arrangement of the parts without departing 45 from the spirit and scope of the invention or sacrificing all of its material advantages, the form hereinbefore described being merely a 50 preferred embodiment thereof.

I claim:

1. An ice cream brick wrapper and carton liner, comprising a sheet of wrapping material provided with slots extending in from 55 an edge and setting off flaps, said slots having rounded inner ends.
2. An ice cream brick wrapper and carton liner, comprising a sheet of wrapping material having a straight edge and a slotted 60 edge, the straight edge being foldable to provide a closed bottom, and the slotted edge providing flaps to close down upon the top of the brick of ice cream, said flaps being separated by slots having rounded inner ends.
- 65 3. The method of folding a wrapper about

the end of a brick of ice cream which comprises providing a plurality of V-shaped slots having rounded apices in an edge thereof, to provide a plurality of flaps at the slotted wrapper edge, folding to rectangular 70 form with the flaps extending and then folding the flaps over the end of the brick of ice cream.
